DRINK STIRRER

Jerold P. Drucker, North Hollywood, Calif., assignor to
Zoo-Piks, North Hollywood, Calif., a partnership

Filed Feb. 6, 1963, Ser. No. 73,462

Term of patent 14 years

(Cl. D44—29)

FIG. 1

FIG. 2

I claim:

The ornamental design for a drink stirrer, substantially as shown.
